UNITED STATES PATENT OFFICE.

WILLIAM S. BARRY, OF GREENWOOD, MISSISSIPPI.

GASOLINE-FEEDING DEVICE.

Application filed March 3, 1922. Serial No. 540,813.

To all whom it may concern:

Be it known that I, WILLIAM S. BARRY, a citizen of the United States, residing at Greenwood, in the county of Leflore and State of Mississippi, have invented certain new and useful Improvements in Gasoline-Feeding Devices, of which the following is a specification.

This invention relates to improvements in gasoline supply means for internal combustion engines and the like, and it has for its objects among others to provide simple and efficient means whereby the gas or oil or other liquid in a tank or container may be delivered to a stationary gas engine or an automobile engine, the said means embodying a combined gasoline refinery, settling tank and reserve tank, without dividing the container or having two separate tanks or containers.

By my present improvement the oil or gas is purified and a settling tank is created and also a reserve tank simply by taking the oil or gas from a level several inches, more or less, above the bottom of the tank and leaving a residue of gas or oil below the pipe which feeds the engine, in which all the water and settlements or impurities are precipitated and retained; this also creates a reserve tank, so that by opening a valve located at the proper place the gas or oil therein can be used in case of emergency, to carry the car to a filling station or the garage or other destination.

Broadly considered, the invention comprises means for providing two independent supplies of gas or oil from the same tank or container, the one from a relatively higher level than the other, but either readily placed in position for immediate use as occasion may require.

Other objects and advantages of the invention will hereinafter appear and the novel features thereof will be specifically defined by the appended claims.

As will be apparent as the description proceeds, the invention is capable of embodiment in a variety of forms, by which the same end is attained, and while I have herein shown a variety of forms it is to be understood that the present invention is not restricted to such particular forms, those herein shown being merely by way of illustration to make clear the object and result attained without relying upon the exact embodiments of the invention which

I have chosen to illustrate in the present invention.

The invention, in such preferred forms of embodiment, is clearly illustrated in the accompanying drawings, which, with the numerals of reference marked thereon, form a part of this specification, and in which—

Figure 1 is a substantially central longitudinal section through a container or tank showing one form of the invention.

Figure 2 is a similar view showing a different form.

Figure 3 is a like view of another form.

Like numerals of reference indicate like parts throughout the several views.

Referring to the drawings,

1, in Figure 1, designates a tank or container of any desired shape and capacity, adapted to contain gasoline, or oil, or other fluid, and from which the same is to be fed by means of a pipe 2. This pipe is shown as pivotally mounted at 3 near the bottom of the tank and adapted to be turned upon such pivot. This may be done in a variety of ways; in the present instance I have chosen to show a rod or the like 4 having its inner end arranged to slidably engage the inner end of the pipe in any suitable manner so that by raising the rod the said inner end of the pipe may be raised when desired, or by lowering the rod the pipe may be placed in a lower plane. Any suitable means may be provided for holding the rod in its adjusted positions. In the present instance the said rod is shown, merely as by way of illustration of one method of securing it where desired, as provided with teeth or serrations 5 which are adapted to engage the walls of the opening in the tank through which the rod passes, being held to such position by a suitable spring or the like 6 which may be enclosed within a suitable housing 7. The rod may be provided with a knob or the like 8 for obvious purposes.

The dotted line position of the pipe in said Figure 1 is the proper position for general use, to supply the gas or oil to the engine. The height of the inner end of the pipe from the bottom of the tank may vary; twelve inches or so will be found satisfactory in most instances. The full line position of the pipe shows its position for draining off the water or other impurities or settling in the lower portion of the tank, the pipe being raised or lowered as occasion may require. When the pipe is in its

raised position, that shown by dotted lines, there is created a settling and emergency tank and filter to cleanse or purify the gasoline while the motor is operating. When 5 the gas in the tank falls to a position where it is below the level of the open end of the pipe while in its dotted line position then the pipe is lowered and if it be necessary to supply gas to the engine it can flow from 10 the reserve supply within the bottom portion of the tank until the garage or filling station is reached. The water and impurities may be withdrawn from the settling tank in any suitable manner. 15 In Figure 2 is shown substantially the same arrangement except that the parts are practically reversed; that is, the pipe 9 is arranged to enter the tank 10 near the top thereof, being mounted for movement, as at 20 11, and adapted to be raised and lowered by means of a rod or the like 12 which has its lower end arranged to slidably engage the inner end of the pipe and the rod provided with teeth or the like 13 to engage 25 the wall of the opening through which the rod passes and there retained by suitable means as a spring 14 encased, as seen at 15. The operation is substantially the same. The dotted line position is that of general 30 operation, taking the liquid from the higher level. The full line position is that for emergency use.

In Figure 3 I have shown the pipe 16 as entering through the bottom of the tank, being of angular form, the portion within the tank being adapted to be raised or lowered by means of the rod 17 having teeth 18, a spring 19, in a housing 20, being provided, similar to the arrangement shown in Figures 1 and 2 and above described. The pipe 40 is pivotally mounted adjacent its angle, as

seen at 21, to permit of the necessary movements thereof. The dotted line position of the pipe is that for general use. The dotted line position is that for emergency use or 45 for draining the lower portion of the tank.

From the foregoing it will be seen that I have devised a simple, efficient and reliable means for the purposes stated, and while the structural embodiments of the invention 50 as hereinbefore disclosed are what I at the present time consider preferable, it will be evident that the same is subject to changes, variations and modifications in detail, proportion of parts, etc., without departing 55 from the spirit of the invention or sacrificing any of its advantages, and I therefore do not intend to restrict myself to such details, proportions or parts, etc., but reserve the right to make such changes, variations 60 and modifications as come properly within the scope of the protection prayed.

What is claimed as new is:—

1. A container, a feed pipe leading therefrom, a pipe pivotally mounted on said feed pipe within the container, and means connected with said pivotally mounted pipe near its free end for moving the pivoted pipe on its pivot to change the level from which the liquid will flow from the container through the first-named pipe. 65

2. A container, a feed pipe extending therein, a pipe pivotally mounted on said feed pipe, and means extending into the container slidably connected with said pivotally 70 mounted pipe in the container adjacent its free end to move the same on its pivot, and means cooperating with said last-named means to hold the pipe in its adjusted positions. 75

In testimony whereroof I affix my signature.

WILLIAM S. BARRY.
